[57] CLAIM

The ornamental design for a hanger for footwear or similar articles, as shown.

DESCRIPTION

FIG. 1 is a front perspective of a hanger for footwear or similar article showing my design;

FIG. 2 is a reduced rear view thereof;

FIG. 3 is a sectional view taken in the direction of the arrows on line 3—3 of FIG. 2;

FIG. 4 is a side view taken from the left of FIG. 2.

FIG. 1

FIG. 2
